UNITED STATES PATENT OFFICE.

FRANKLIN H. HERTZLER, OF LANCASTER, PENNSYLVANIA.

PUMP.

Application filed October 20, 1922. Serial No. 595,611.

To all whom it may concern:

Be it known that I, FRANKLIN H. HERTZLER, a citizen of the United States, residing at Lancaster, in the county of Lancaster 5 and State of Pennsylvania, have invented new and useful Improvements in Pumps, of which the following is a specification.

This invention relates to pressure generators or pumps and has for an object the 10 provision of a pump wherein pressure is generated by centrifugal forces.

Another object of the invention is the provision of a rotary pump having a novel construction and arrangement of impeller 15 vanes and guide vanes, whereby direct radial passages for the fluid passing through the pump are provided, and reaction against the direction of rotation prevented.

Another object of the invention is the 20 provision of a novel arrangement of impeller and guide vanes, whereby all foreign matter passing through the pump may be forced through the passages thus provided, before said vanes entirely pass one another.

With the above and other objects in view, 25 the invention further includes the following novel features and details of construction, to be hereinafter more fully described, illustrated in the accompanying drawings 30 and pointed out in the appended claims.

In the drawings:

Figure 1 is a vertical sectional view of a single stage pump constructed in accordance with the invention.

Figure 2 is a section at right angles to Figure 1.

Figure 3 is an elevation partly in section showing a different arrangement of vanes and means whereby the suction at the pump 40 intake may be increased.

Figure 4 is a view at right angles to Figure 3, parts being also shown in section.

Figure 5 is a view in diagram illustrating 45 one arrangement of impeller and guide vanes.

Figure 6 is a similar view illustrating another arrangement.

Figures 7 and 8 are like views showing still other arrangements.

Referring in detail to the drawings and more especially to Figures 1 and 2, the invention is shown as comprising a casing 10 which is mounted upon a suitable base 11 and which is provided at one side with an 50 intake 12 and at its bottom with a discharge 13.

Mounted in suitable bearings and extending transversely of the casing 10 is a shaft 14, upon which may be mounted a pulley or other wheel 15 to provide for rotating the 60 shaft 14.

Mounted upon this shaft 14 is a rotor or impeller, which includes vanes 16, the said vanes being spaced apart and formed to provide radially extending passages 17 65 having substantially parallel walls so that the width of the passages will be substantially the same throughout their length. The outer edges of the vanes 16 are beveled as shown at 18, the said bevel being relative to the direction of rotation of the vanes 10, as shown by the arrow. The amount of this bevel depends upon the deflection from a tangent to the periphery of the impeller, while the vanes are moving through 70 a distance equal to the distance between two consecutive vanes.

Surrounding the impeller and disposed concentrically are spaced guide vanes 19, the spaces between these vanes providing 75 substantially parallel passages 20, with which the passages 17 are brought into register during the rotation of the impeller. The outer ends of the passages 20 are offset or inclined with respect to their lengths, 80 as shown at 21, so that the fluid passing therethrough will be deflected in the same direction, irrespective of the direction of rotation of the impeller. By beveling the outer ends of the impeller vanes and the 85 inner ends of the guide vanes, free passage of liquid through the vane passages is provided. In other words, no shoulders or abutments are present across the adjacent ends of the vane passages to impede the 90 passage of the liquid as the impeller vanes rotate across the passages between the guide vanes.

The number and length of the vanes 16 and 19 may vary, the lengths of the vanes 100 and the width of the passages provided between them depending upon the size and character of the pump. The length of the vanes 16 and 19 may be relatively varied, that is, the vanes 16 may be shortened and 105 the vanes 19 lengthened, and vice versa, while the length of the combined passages 17 and 20 will remain substantially the same for a pump of a given character.

As illustrated in Figures 1 and 2, the 110 guide vanes are arranged substantially parallel to the direction of rotation of the

impeller, while in Figures 3 and 4, these 5 guide vanes which are indicated at 22 are inclined and are arranged in double formation, being separated by a partition 23. This permits of the passage of foreign matter from the impeller passages into the guide vane passages, before the impeller and guide vanes pass one another. In addition, the arrangement of the vanes 22 permits of intake passages 24 being arranged upon opposite sides of the impeller which may be in communication with a common supply pipe or conduit 25. A single discharge outlet 26 is provided.

10 15 Various other arrangements of vanes may be employed such for example as is illustrated in Figure 6, wherein the impeller vanes 27 are substantially V-shaped and the guide vanes 29 are also V-shaped but are disposed oppositely to the vanes 27.

15 20 In Figure 7 the arrangement is substantially the same as that illustrated in Figure 4, the view serving to illustrate the relative positions of the vanes 22 and 17.

25 30 In Figure 8 the rotor vanes 29 and the guide vanes 30 are relatively inclined and are adapted for use in a pump having a single intake. This is also true of Figure 9, wherein the impeller vanes 31 are axially disposed and the guide vanes 32 are disposed at an incline.

35 Again referring to Figures 3 and 4 of the drawings, the shaft 33 upon which the impeller is mounted, has also mounted thereon suction fans 34, which serve to increase

the suction through the intake passages and therefore act to increase the pressure generated by the pump.

40 The invention is susceptible of various changes in its form, proportions and minor details of construction and the right is herein reserved to make such changes as properly fall within the scope of the appended claims.

45 Having described the invention what is claimed is:—

1. A pump comprising a housing having inlet and outlet ports, a rotor operating within the housing, spaced vanes carried by the rotor, spaced stationary vanes disposed concentrically around the rotor carried 50 vanes, all of said vanes being arranged to provide passages of substantially the same width throughout their lengths and said rotor carried vanes being beveled inwardly at their outer ends in the same direction as 55 their direction of rotation.

2. A pump comprising a housing having inlet and outlet ports, a rotor operating within the housing, spaced vanes carried by the rotor, spaced stationary vanes disposed 60 concentrically around the rotor carried vanes, all of said vanes being arranged to provide direct radial passages of substantially the same width throughout their lengths and said rotor carried vanes being 65 beveled inwardly at their outer ends in the same direction as their direction of rotation.

In testimony whereof I affix my signature.
FRANKLIN H. HERTZLER.
